N°. 992.

*Design for a Stove Plate
By N. S. Vedder and Ezra Ripley of Troy, N. Y.
Assignors to Louis Poller of the same place*

Patented Feb. 23, 1858.

Dec. 992

N. S. Vedder, and Ezra Ripley, of Troy, N. Y.

Designers to

Louis Potter, of same place

Letters Patent No. 992. Dated Feb. 23rd 1858.

The schedule referred to in these Letters Patent & making part of the same.

To all whom it may concern:

Be it known that we, N. S. Vedder, and Ezra Ripley, each of the city of Troy, in the county of Rensselaer, and state of New York, have jointly invented or produced a new and original design, for a Plate of a Box Stove, to be called the "Tropic", and we do hereby declare that the following is a full & exact description of the same, reference being had to the annexed photographic drawing making a part of this specification.

Our ornamental design for a stove plate consists of the central pine-apple-like ornament, a, supported at its sides by the scrolls and leaves b, c, d, e, f, and b', c', d', e', f', backed by the check-work ground g, all substantially as shown by the annexed photograph.

What we claim as our invention or production, and desire to secure by Letters Patent, is the ornamental design for a stove End plate herein described and represented by the annexed photographic drawing.
